(57) CLAIM

The ornamental design for a set of icons for portions of a display screen, as shown and described.

DESCRIPTION

The FIGURE is a front view of a set of icons for portions of a display screen showing our new design.

The broken lines illustrate portions of a display screen. The icons are arranged on the drawing sheet for the convenience of display. The broken lines and the arrangement of the icons form no part of the claimed design.

1 Claim, 1 Drawing Sheet
